UNITED STATES PATENT OFFICE.

JOHN P. FULLILOVE, OF SHREVEPORT, LOUISIANA.

COMBINED DRILL AND REAMER.

1,411,484.

Specification of Letters Patent.

Patented Apr. 4, 1922.

Application filed June 22, 1920. Serial No. 390,750.

To all whom it may concern:

Be it known that I, JOHN P. FULLILOVE, a citizen of the United States, residing at Shreveport, Louisiana, have invented certain 5 new and useful Improvements in a Combined Drill and Reamer, of which the following is a specification.

This invention comprises a combined drill-bit and reamer. While its application is un- 10 restricted, it is especially adapted for use in the drilling of oil and gas wells and the like.

It is contemplated among the objects of the invention to provide a combined drill-bit and reamer, the reamer comprising a 15 blade or plurality of blades normally housed within the outer walls of the drill-bit and so arranged that they may be forced outwardly beyond the plane of the wall of the bit-head to enlarge or undercut the hole 20 made by the bit.

It is also contemplated to arrange the reaming instrumentality so that the pump and pressure medium ordinarily used in connection with a well drilling rig may be utilized as a means for outwardly extending the 25 reamers; to so arrange ducts, channels and chambers for the pressure medium that when the reamers arrive at a predetermined position of extension there will be a pronounced 30 change in the pressure which may be used as an indication that such predetermined position has been reached; also, to so house the reamers within the bit-head that they will form practically an integral part of it when 35 closed and even when opening will be unaffected by the jarring, will have no openings within which foreign matter may lodge, and will have a positive bearing under all conditions at a plurality of points within the bit- 40 head.

The pivoting of the reamers at the upper portion of the drill-bit so that withdrawal of the bit from the hole will close the reamers; the shape of the reamer blades; the ar- 45 rangement of the pressure ducts and cham- bers to produce a flexibility of the reamer blades which permits them to conform with irregular wall surfaces; and the simple, practical arrangement of the parts for assem- 50 blage, are features of the invention which will in part be apparent and in part be brought out more fully in the description which follows.

Drawings illustrating an embodiment of 55 the invention are appended, and in these:—

Figs. 1 and 2 are views in front elevation showing an embodiment of the invention with parts in two positions;

Figs. 3, 4 and 5, are views in transverse section on lines 3—3, 4—4, and 5—5, respectively;

Figs. 6 and 7, are views in central vertical section and seen from the front and side respectively.

In these views, 1 designates a drill-bit or 65 bit head, provided with a cutting edge 2 at one end, and at the other end secured to a pipe 3. This pipe is in communication with a source of pressure medium and forms a part of a drill stem not shown. 70

The body portion of this head is pref- 75 erably made in two parts suitably secured together when assembled, as by bolts or the like 4. Each section is hollowed out on the inside face thereof to constitute a chamber 5, 75 or compartment within which there is housed a plurality of reaming instrumentalities 6.

These reamers comprise blades having tapered or beveled edges 7 to constitute cutting edges and are hung from a pivot 8 at 80 the upper portion of the drill bit. The upper portion of each blade is rounded in the shape of an arc of a circle with the pivot 8 as a centre and the upper portion of the chamber 5 is correspondingly shaped. The 85 lower portion of each chamber is shaped to conform with the lower portion of each blade, thus providing a double bearing for the blade which is supported on the pivot 8, and the lower portion of the chamber. 90 These blades are disposed face to face within the chamber or compartment 5 and normally housed therein. The chamber is provided with openings through which the blades may be extended as shown, the arrangement be- 95

ing such that the outer edge of each blade constitutes practically a continuation of the corresponding edge of the drill bit when the blade is in closed position. This prevents the entrance of any foreign matter to the 100 chamber and insures free working of the blades. A packing 9 may also be provided around the edges of the openings through which the blades are extended, and at the upper portion of each blade there is a means 105 for limiting its outward movement, the same here comprising a shoulder 10 adapted to bear against the upper edge of the opening when in extended position.

Means are provided for extending the 110

blades outwardly to undercut or enlarge a drill hole, and to this end there are shown channels 11 in the head of the drill bit. These are in communication at one end 5 through pipe 3, with a source of pressure medium and at the other end communicate with the chambers 5 at the back edge of each blade. It will be understood that by leading the pressure fluid back of the blade 10 the latter will be forced outwardly until limited by the shoulder 10.

Means are provided whereby the pressure acting on the back of the blades will be automatically graduated so that while less 15 at the beginning of the movement of the blade, it will be increased in direct proportion at a predetermined rate in proportion to the distance the blade is extended from the side of the bit. As here shown, 20 this is effected by providing the circular portion of each blade, at the point where it would cross one of the ducts 11, with a cut away portion 12, hollow in cross section as shown in Fig. 5, and restricting the opening 25 when in closed position, but gradually enlarging as shown in Fig. 6, until, at its largest portion it gives an unrestricted passage for pressure medium through the channel 11.

Means are provided for indicating when 30 the pressure medium has forced the blades outwardly to a predetermined position and for providing free passage of the pressure medium into the hole after this point has been reached. As here shown this is effected 35 by providing openings 13 in the side of the drill bit and openings 14 in the outer portion of each blade, so arranged as to be in communication with the openings 13 when the blades are in extended position. The 40 inner ends of the openings 14 are in communication with larger ports 15 in each blade and so arranged that when the blades are extended as shown in Fig. 5, there will be free access between the channels 11 back of 45 each blade and through the ports and openings with the drill hole. It will be apparent that when this point is reached there will be a sudden falling off of the pressure medium due to the opening of the ducts, 50 which may be utilized in changing the position of the reamers.

In actual use the pressure is kept at a maximum capacity of the pump until the predetermined position of the blades is reached, 55 or when channels 15 are in communication. This is arranged so as to be the extreme extension of the blades. At this point the release of pump pressure will indicate to the operator that the blades are in full open position. This gives positive information of 60 this fact as there will be no release until both blades have reached full extended position. Opening of one blade only will not effect a release of the pump pressure.

65 By arranging the reamers in the manner

shown, there is a completely closed drill head with no openings into which foreign matter can enter to interfere with the working of the parts. The openings 13 are comparatively small, situated in a position where there is slight liability of picking up any foreign matter and the pressure medium being back of these openings will drive out anything that may lodge there. 70

The blades being pivoted at the upper portion of the drill bit may be easily closed by merely withdrawing the bit so that the blades are forced inwardly by the restricted neck of the hole or the casing which may 75 in certain instances be employed.

While the invention is disclosed in the embodiment herein described, it will be understood that I do not wish to be limited to the precise form of this disclosure, as many changes may be made in the construction and 80 general arrangement of the parts without departing from the spirit of the invention or its scope as set forth in the claims. 85

What I claim is:—

1. A reamer comprising a body having a 90 chamber and channels for the passage of fluid under pressure, bits pivoted within said chamber and having ducts gradually increased in depth from one end whereby the passage of the fluid under pressure through 95 said ducts from said channels forces said bits outwardly.

2. A reamer comprising a body having a chamber and channels for the passage of fluid under pressure, bits pivoted within 100 said chamber and having ducts gradually increased in depth from one end whereby the passage of fluid under pressure through said ducts from said channels forces said bits outwardly, the walls of said chamber being provided with openings adapted to be closed by 105 said bits.

3. A reamer comprising a body having a chamber and channels for the passage of fluid under pressure, bits pivoted within said chamber and having ducts gradually increased in depth from one end whereby the passage of fluid under pressure through said ducts from said channels forces said bits outwardly, the walls of said chamber being provided with openings adapted to be closed by said bits, said bits being provided with 110 openings adapted for registration with the openings in said channel. 115

4. A reamer comprising a body having a 120 chamber and channels communicating with the chamber and adapted for the passage of fluid under pressure, bits pivoted within said chamber and having ducts establishing communication between said chamber and said 125 channels, said bits being moved outwardly by the pressure of the fluid passing through said ducts.
